UNITED STATES PATENT OFFICE

98,578

DESIGN FOR AN ASH RECEIVER OR SIMILAR ARTICLE

George W. Emmert, Detroit, Mich.

Application December 5, 1935, Serial No. 59,915

Term of patent 3½ years

To all whom it may concern:

Be it known that I, George W. Emmert, a citizen of the United States, residing in the city of Detroit, county of Wayne, and State of Michigan, have invented a new, original, and ornamental Design for an Ash Receiver or Similar Article, of which the following is a specification, reference being had to the accompanying drawing, forming part thereof, in which Fig. 1 represents a side elevational view of the article, showing my design,

Fig. 2 represents a similar elevational view showing the ash receiving cup in tilted or closed position and Fig. 3 represents a top plan view of the article shown in Fig. 1.

I claim:

The ornamental design for an ash receiver or similar article, substantially as shown and described.

GEORGE W. EMMERT.
